UNITED STATES PATENT OFFICE.

JAMES DANIEL JOYCE, OF PHILADELPHIA, PENNSYLVANIA.

BOBBIN-WINDING MACHINE.

Application filed October 30, 1922. Serial No. 598,008.

To all whom it may concern:

Be it known that I, JAMES D. JOYCE, citizen of the United States, residing at Philadelphia, in the county of Philadelphia and 5 State of Pennsylvania, have invented certain new and useful Improvements in Bobbin-Winding Machines, of which the following is a specification.

This invention relates to upright spindle 10 winding machines known as bottle bobbin winders, the object in view being to simplify and improve the existing method of winding on to bottle bobbins and to improve upon the existing method of winding on to cones 15 and conical shaped bobbins by effecting and maintaining a definite, unchanging relationship between the growth in height and thickness of the yarn package and the changing height of the yarn guide known as the 20 builder, and is a refiling of application Serial Number 449,045, filed March 2, 1921.

In order to produce a properly wound bobbin it is necessary to have the yarn laid evenly in quantity and tension from commencement to finish of the package, each 25 layer containing the same quantity in length of yarn and each layer being equidistant from all others—hence the necessity of having the changing height of the yarn guide 30 controlled by the changing height of the yarn package. This should be automatic and dependent rather than independent as is usually the case with geared controls which do not seem to lend themselves to 35 proper adjustment and most certainly do not maintain it where bobbins are of variable thickness.

Heretofore the chief objection to automatic building has been due to the fact that 40 the general construction of the spindle and attendant mechanism would not accommodate itself to defective or broken yarns. Since all yarns are imperfect it is necessary 45 to improve the spindle construction. Such feature is claimed as the base of this invention or development and specially is as follows: In the existing undesirable construction the spindle carrying the bobbin is 50 revolved by means of a disk which is permanently mounted and fixed to the spindle, being rotated by contact with a wheel operating and revolving at right angles thereto. Were operation continuous, the objection

would not be reached, however, it becomes necessary for purposes of splicing yarns to 55 stop the rotation of the bobbin by raising what will now be recognized as the friction disk up and off from the friction wheel. Its attendant objection will now be evident since lifting the friction disk which is fixed 60 to the spindle carrying the bobbin is also lifting the bobbin finally achieving the ultimate objection of changing the relative height of bobbin and yarn guide. The builder governing the yarn guide when in 65 continuous operation is lightly touched by each additional layer of yarn which through the rotation of the bobbin is turned slightly and being mounted on a threaded stem is caused to rise to the new desired height, 70 which is also the new height of the yarn package, but when the bobbin is stopped, through not revolving, it does not change the height of the builder but does change the height of the bobbin, as previously ex- 75 plained causing heavy contact or bump of yarn package and builder, resulting in case of hard yarn, in a bent builder stem; in soft yarns the package is dented, and in very delicate yarn the strands are stretched and 80 broken. Again, if the builder is lifted by hand to avoid bumping, it consumes time, and if not returned to its original place commences building at a higher point, re- 85 sulting in an uneven package which is extremely undesirable. In continuous operation the existing method is successful, but not successful when the machine as a whole is running but with an individual spindle or spindles stopped, and this because the spindle carrying the bobbin is lifted thereby 90 changing the relation of package and builder. The solution of this problem and the object of this invention is to lift the friction disk, thereby stopping the rotation 95 of the spindle and bobbin but without raising the spindle, consequently leaving an unchanged relationship of yarn package and builder avoiding the aforementioned bent builders, dented packages and stretched or 100 broken yarns.

The invention to effect this consists of the construction, combination and arrangement herein fully described, illustrated and claimed.

In the accompanying drawings:

Figure 1 is a side view of a bobbin winding machine.

Figure 2 is a fragmentary front elevation thereof.

5 Figure 3 is a side elevation of one of the bobbin winding units showing the driven friction disk lifted.

10 Figure 4 is a similar view showing the friction disk in working relation to the friction drive wheel.

15 Figure 5 is a fragmentary plan view showing the manually operated cam for actuating the lifting lever.

20 The improved bobbin winding unit comprises a bracket A having upper and lower arms *a* and *a'* respectively, said arms being formed with upper and lower bearings *a²* and *a³* for a vertical stem or spindle B which rotates freely therein. Any number of bobbin winding units may be mounted in a single machine, the latter being partially shown in Figures 1 and 2 wherein the relation of one bobbin winding unit thereto is clearly shown.

25 The spindle driving means embodies in the present invention a driven friction disk C which is mounted on the stem B so as to rotate therewith and also be capable of being slid upwardly and downwardly thereon, as indicated in Figures 3 and 4. The connection between the disk C and the spindle B embodies a clutch face *c* on the disk C and another clutch face *c'* on the spindle B. The clutch faces are of such extent that the disk C may be raised and lowered without throwing the clutch faces out of engagement with each other. Therefore, the disk C is always in driving connection with the spindle B. When the bobbin winding unit is in operative condition, the disk C rests upon and is directly driven by a friction drive wheel D, as shown in Figure 4. As soon as the disk C is slightly lifted, the rotation of the spindle B ceases.

30 The means for raising and lowering the disk C embodies a two-armed lever E, said lever comprising an upper arm *e* and a lower curved arm *e'*. The lower arm *e'* carries an anti-friction roller *f* which bears against the under side of the friction disk C. The upper arm *e* carries an anti-friction roller *f'* which bears against the working face *g* of a cam member G, the latter being provided with an operating handle *g'*. The cam face *g* is quadrant-shaped and is formed on the highest portion thereof with a dwell surface *g²*, and when said dwell surface is in engagement with the roller *f* the lever E is held in its disk-lifting position. The parts 35 will be held in this position until the cam G is turned in the reverse direction for lowering the disk C. The hub of the cam G is rotatable axially around and upon the spindle B and rests upon the upper bearing 40 *a²*. A collar *h* is fast on the stem B above

the cam G, said collar *h* resting upon the cam. Another collar *h'* is fast on the stem B just beneath the upper bearing *a²*. The collars *h* and *h'* prevent endwise movement of the stem B and thus said stem or spindle 70 is prevented from moving upwardly and downwardly.

By reason of the construction above described the bobbin may be wound with the utmost accuracy and with an even tension 75 on the yarn throughout its entire length from the inside to the outside layers and from base to tip. The yarn must be laid in even layers on and around the bobbin, thereby assuring an even thickness in the 80 winding and enabling the yarn to be built up on the bobbin, controlled from the package itself. When the rotation of the spindle is stopped by turning the cam, the bobbin remains always at the same elevation, it being impossible for the bobbin spindle or stem to move either in an upward or a downward direction. The result is a bobbin evenly wound and free from 85 bumps and there is no liability of the yarn 90 being unduly stretched, which would cause the builder stem to bend or the yarn package to be dented.

I claim:

1. In a winding machine, a non-lifting winding spindle, spindle driving means embodying two contacting friction members in driving connection with the spindle, and means for lifting the driven friction member out of contact embodying a lifting member, and a bell crank lever carried on the spindle and revoluble about the axis of the spindle. 95

2. In a yarn winding machine, the combination of the frame thereof, a vertically arranged winding spindle journalled therein, means to prevent longitudinal movement of the spindle relatively to the frame, a driving wheel, a whirl disc slidable longitudinally on the spindle and adapted to rest normally in driving engagement with the wheel, means causing the spindle to rotate with the disc and permitting the disc to be raised and lowered from and into engagement with the wheel, and a horizontally movable lever provided with a cam surface and arranged to raise the disc when the lever is moved. 105

3. In a yarn winding machine, the combination with a frame, of a vertically arranged winding spindle journalled therein, means to prevent longitudinal movement of the spindle relatively to the frame, a driving means for revolving the spindle operatively connected therewith, and a horizontally movable lever for disconnecting said driving means and spindle. 115

4. In a yarn winding machine, the combination with a frame, of a vertically arranged winding spindle journalled therein, 120

means to prevent longitudinal movement of the spindle relatively to the frame, a driving means, a separable connecting means between said driving means and the spindle normally in driving relation, said connecting means being movable relatively to the spindle and the driving means, and a lever

provided with a cam surface arranged to separate said connecting means from the driving means and to lock in said position 10 until turned in reverse direction.

In testimony whereof I have affixed my signature.

JAMES DANIEL JOYCE.
